(57) **CLAIM**

The ornamental design for a carton with fitment, as shown and described.

DESCRIPTION

FIG. 1 is a perspective view of the carton with fitment according to the present invention;

FIG. 2 is a front view of the carton with fitment as seen in FIG. 1;

FIG. 3 is a back view of the carton with fitment as shown in FIG. 1;

FIG. 4 is a left side view of the carton with fitment as shown in FIG. 1;

FIG. 5 is a right side view of the carton with fitment as shown in FIG. 1;

FIG. 6 is a top view of the carton with fitment as shown in FIG. 1;

FIG. 7 is a bottom view of the carton with fitment as shown in FIG. 1;

FIG. 8 is an enlarged perspective view of the fitment as shown in FIG. 1;

FIG. 9 is an enlarged back view of the fitment as shown in FIG. 3;

FIG. 10 is an enlarged left view of the fitment as shown in FIG. 4;

FIG. 11 is a top view of the fitment as shown in FIG. 6;

FIG. 12 is a perspective view of the carton with fitment according to the present invention with the fitment in an open position;

FIG. 13 is a front view of the carton with fitment according to FIG. 12;

FIG. 14 is a left side view of the carton with fitment according to FIG. 12; and,

FIG. 15 is an enlarged perspective view of the fitment as seen in FIG. 12.

The broken lines shown in the drawing disclosure depict environmental features that form no part of the claimed design.
